EXCAVATING DIPPER

Original Filed Feb. 21, 1927

INVENTOR.
WALTER E. MILEY.

Samuel A. Reid
ATTORNEY

UNITED STATES PATENT OFFICE

WALTER E. MILEY, OF MARION, OHIO, ASSIGNOR TO THE MARION STEAM SHOVEL COMPANY, OF MARION, OHIO, A CORPORATION OF OHIO

EXCAVATING DIPPER

Original application filed February 21, 1927, Serial No. 169,786. Divided and this application filed September 7, 1927. Serial No. 218,061.

This invention relates to excavating dippers such as are commonly employed in connection with power operated shovels, and relates more particularly to the construction 5 of the dipper front and the manner of mounting the teeth thereon.

One object of the invention is to provide a dipper in which the inner surface of the dipper front will be free from obstructions, 10 which would interfere with the free movement of material through the dipper.

A further object of the invention is to provide a dipper front of such a character that the dipper teeth when mounted thereon will 15 be so arranged with relation to the front that they will provide ample clearance for the latch plate at the lower edge of the front.

Other objects of the invention will appear as the device is described in detail.

20 In the accompanying drawings Fig. 1 is a side elevation, partly in section, of a dipper embodying my invention; Fig. 2 is an elevation of the inner side of the dipper; Fig. 3 is a section taken on the line 3—3 of Fig. 2; 25 Fig. 4 is an elevation of the inner surface of a portion of a dipper front embodying a slightly modified form of the invention; and Fig. 5 is a section taken on the line 5—5 of Fig. 4.

30 The present application is a division of the application filed by me February 21, 1927, Serial No. 169,786 for patent on Excavating dippers. In the drawings I have illustrated one embodiment of my invention, with a 35 slight modification thereof, but it will be understood that this embodiment has been chosen for the purposes of illustration only and that the invention may take various forms without departing from the spirit 40 thereof.

As here shown, the dipper comprises a front 1 which is slightly curved in shape and is provided with rearwardly extending side portions 2, the usual teeth 3 being mounted 45 on the upper edge of the front. A back plate 4 is connected with the side portions of the front 1, by means of side members which, in the present instance, consist of lower portions 5 and upper portions or top bars 6, the 50 several parts of the dipper being rigidly

connected one to the other by rivets or the like. The lower or discharge end of the dipper is provided with a door 29 which, as here shown, is carried by arms 30 which are curved upwardly and rearwardly and pivotally mounted on lugs 31 carried by the back 4. The back is also provided with other lugs 32 by means of which the dipper is connected with the dipper arm or handle. A latch bar 33 carried by the door 29 cooperates with a latch plate 35 secured to the lower edge of the dipper front 1. This latch plate may take various forms and may be mounted on the front in various ways but, as here shown, the front is provided in its lower edge with a recess 36, a portion of which extends entirely through the front and the plate is mounted in this recess and is provided with an opening 40 to receive the end of the latch bar.

70 The dipper teeth 3 are usually bifurcated to receive the upper or cutting edge of the dipper front and the inner portion 22 of each tooth extends into the dipper and the outer portion 23 thereof extends downwardly along the outer surface of the front. In the ordinary construction the inner portions 22 of the teeth rest upon the inner surface of the front and therefore project inwardly such a distance as to provide substantial obstructions to the passage of material through the dipper, these obstructions being particularly objectionable when the dipper is working in material which has a tendency to wedge or pack between the teeth. In order to provide the dipper front with a substantially smooth inner surface, free from obstructions, 75 I have provided the inner surface of the front with recesses adapted to receive the inner portions of the teeth and of such a depth that the inner surfaces of the teeth will be substantially flush with the inner surface of the front. Preferably the upper portion of the dipper front is offset, as shown at 24, to provide the inner surface thereof with

80 a recess 25 extending across the upper end thereof, the upper portion of the outer surface of the front, being offset, projects beyond the lower portion of that surface. As 85 here shown, the cutting edge of the front 100

is provided with notches to receive portions of the bifurcated teeth, which notches merge into the recess of the offset portion 24 of the front. When the teeth are seated in the 5 notches the inner portions 22 thereof extend into the recess which is of a depth approximately equal to the thickness of the portions 22 of the teeth so that the inner surfaces of these teeth will lie in substantially the same 10 plane with the inner surface of the front. The spaces between the inner portions 22 of the dipper teeth are preferably closed by fillers which fit snugly between the teeth and are of such thickness that their inner 15 surfaces are in substantially the same plane with the inner surfaces of the teeth and of the front and the forward portions of the fillers are beveled toward the cutting edge of the front. These fillers divide the offset portion 20 of the front into a series of recesses which are arranged in line with and merge into the respective notches and in which the portions 22 of the teeth fit. The fillers may be of any suitable character and in Figs. 2 25 and 3 they are shown at 26 as formed separate from the front and rigidly secured thereto by rivets 27. In Figs. 4 and 5 the fillers are shown at 28, as formed integral with the dipper front. In this latter instance the 30 fillers are of the same general shape and arrangement as those shown in Figs. 2 and 3 but instead of being separately formed and subsequently attached to the front they are cast in one piece with the front thus providing the front with a series of recesses as 35 above set forth.

Because of the offset position of the upper portions of the front the outer portions 23 of the teeth, which extend across the offset portion 40 of the front and downwardly along the outer surface of the front, are caused to extend a greater distance from the front than they otherwise would do and thus provide, in the bank in which the dipper is working, 45 a deeper path or increased clearance for the latch plate at the lower end of the front, thereby reducing the wear on the latch plate by preventing its engagement with the bank in which the dipper is working, which it 50 usually has when the teeth are mounted in the ordinary manner.

While I have shown and described one embodiment of my invention I wish it to be understood that I do not desire to be limited to 55 the details thereof as various modifications may occur to a person skilled in the art.

Having now fully described my invention, what I claim as new and desire to secure by Letters Patent, is:

60 1. In an excavating dipper, a front having recesses in the inner surface and at the upper edge thereof, each adapted to receive a portion of a dipper tooth, said inner surface extending in a substantially straight line from 65 the lower edge of each recess to the lower por-

tion of said front, each recess having its bottom offset outwardly from and substantially parallel with the inner surface of said front and being of a depth substantially equal to the thickness of said portion of said tooth, 70 and said front having parts between adjacent recesses substantially flush with said inner surface and said inner portions of said tooth.

2. In an excavating dipper, a front having 75 its upper portion offset outwardly to project beyond the plane of the outer surface of said front and to form a recess in the inner surface of said front, and a dipper tooth secured to the upper edge of said front and having a part extending into said recess, said part being of a thickness substantially equal to the depth of said recess, said tooth also having an outer portion extending across the offset portion of said front and downwardly 80 along the outer surface of said front to a point a substantial distance below said offset portion.

3. In an excavating dipper, a front having 85 a smooth inner surface provided at its upper edge with a transverse recess, dipper teeth secured to said front and each having a part extending into said recess and of a thickness substantially equal to the depth of said recess, and fillers formed separate from said front 90 and rigidly secured thereto between adjacent teeth and having their inner surfaces substantially in the plane of the inner surface of said teeth and said front.

4. In an excavating dipper, a front having 95 its upper portion offset outwardly to form a transverse recess in the inner face thereof and having a straight smooth inner surface extending from said recess to the lower portion of said front, dipper teeth secured to the upper edge of said front and each having a part extending into said recess, and fillers arranged in said recess between adjacent teeth and rigidly secured to said front, said parts of said teeth and said fillers being of such 100 thickness that their inner surfaces will lie substantially in the plane of the inner surfaces of said front.

In testimony whereof, I affix my signature hereto.

WALTER E. MILEY.
